(57) **CLAIM**

The ornamental design for a tire for motorcycle as shown and described.

DESCRIPTION

1. Tire for motorcycle

1.1 : Front

1.2 : Back

1.3 : Top

1.4 : Bottom

1.5 : Right

1.6 : Left

1.7 : Perspective

1.8 : Enlarged

The ghosted or low contrasted showing of portions of a tire for motorcycle do not form part of the claimed design; fig. 1.1 is a front elevation view of the tire for motorcycle; fig. 1.2 is a back elevation view thereof; fig. 1.3 is a top plan view thereof; fig. 1.4 is a bottom plan view thereof; fig. 1.5 is a right side elevation view thereof; fig. 1.6 is a left side elevation view thereof; fig. 1.7 is a perspective view thereof; and fig. 1.8 is an enlarged partial front elevation view thereof, wherein the enlargement area is indicated by the broken line bracket marked 1.8 in fig. 1.1.
